UNITED STATES PATENT OFFICE.

FRANK V. RISINGER, OF LAKWOOD, OHIO.

BURNER GRID AND PROCESS OF MAKING THE SAME.

Application filed October 13, 1925. Serial No. 62,289.

The present invention relates to a grid for gas burners and the process of making the same, and has for its object primarily to provide a highly efficient grid which is of simple and substantial construction and can be manufactured at very small cost.

Further objects of the invention are to provide a grid for gas burners which is well adapted for use in connection with radiant heaters, which will produce a high temperature flame without back-firing, which will not become overheated, which prevents "spreading" of the flame, and which will operate practically noiselessly and bring about a very efficient combustion of the gas.

The invention also contemplates a gas burner which brings about a thorough mixing of the air and gas and a uniform distribution thereof to the different parts of the burner grid, so that substantially perfect combustion of the gas is produced and the radishants are all heated in a uniform manner.

The invention also contemplates a novel process of manufacturing the grids by cutting or sawing slits in the edges of metal bars and then assembling the metal bars in an edge to edge relation, so that the slits provide burner openings which have a substantially uniform cross section from top to bottom and do not have enlarged or flared upper ends to produce flaring or "spreading" of the flame.

For a full understanding of the invention reference is to be had to the following description and accompanying drawings, in which

Figure 1 is an enlarged top plan view of one of a pair of complementary grid sections.

Figure 2 is an edge view thereof.

Figure 3 is a plan view of two of the complementary grid sections in an assembled relation.

Figure 4 is a perspective view of one end of the channeled mouth of the burner manifold showing the manner of fitting the grids therein.

Figure 5 is a vertical transverse sectional view through the upper end of the manifold with the grids in position therein.

Figure 6 is a side elevation of the burners with portions thereof broken away and shown in section.

Figure 7 is a top plan view thereof.

Figure 8 is a horizontal sectional view

through the manifold section of the burner, taken on the line 8-8 of Figure 6.

Figure 9 is a top plan view of the lower section of the burner comprising the Bunsen tube and the mixing chamber.

Figure 10 is a vertical sectional view through the mixing chamber on the line 10-10 of Figure 9.

Figure 11 is a transverse sectional view through the manifold taken substantially on the line 11-11 of Figure 6.

Corresponding and like parts are referred to in the following description and indicated on all of the views of the drawings by like reference characters.

The grid of my invention is adapted to be employed in connection with a burner such as that which is illustrated by Figures 6 to 10 inclusive of the drawings. This burner comprises a manifold A which flares upwardly and is provided at its upper end with a narrow longitudinally extending channeled seat B within which the burner grid is fitted. The side walls 1 of the manifold have a spaced and substantially parallel relation and are connected at intervals just below the seat B by the cross bars or webs 2 which are suitably threaded to receive the grid fastening screws 3. The lower end of the manifold A terminates in a circular neck which is connected by a coupling C to a corresponding opening in the top of the mixing chamber D. This mixing chamber extends rearwardly from the end of the Bunsen tube E. The Bunsen tube is of a suitable length to insure a proper feeding of the air as the gas passes through the same. The air and gas are given a swirling motion as they are directed from the Bunsen tube into the mixing chamber. This results in a thorough mixing of the air and gas before they pass upwardly through the coupling C into the manifold A.

The grid is formed in sections which are fitted in the channel shaped seat B of the manifold and secured in position therein by the screws 3. Each section of the grid is divided longitudinally into complementary strips 4, one of which is shown by Figure 1. One edge of the complementary strip has a series of comparatively narrow slits 5 sawed or otherwise cut therein, the inner ends of the slits being substantially parallel to the near edges of the strips so that the openings formed by the slits are substan-

tially uniform in cross section from the top to the bottom of the strip. The two complementary strips 4 of each grid section are assembled in an edge to edge relation with the slit edges thereof together and the slits are preferably formed in the strips in corresponding positions so that the slits in the two strips register with each other when the strips are assembled. The registering slits 10 form long and narrow burner openings which are uniform in cross section from the bottom of the grid to the top thereof, and which are sufficiently narrow to prevent any possibility of back-firing. When the two 15 complementary strips 4 are assembled, as shown by Figure 3, the grid section which is produced has a width corresponding to the width of the channel shaped seat of the manifold so that it will fit between the side 20 walls of the seat and be held against lateral displacement thereby. The ends of the strips 4 of the grid sections have the inner corners thereof provided with quarter circular notches 6, the notches of the two strips 25 forming a semi-circular opening adapted to receive the shank of one of the screws 3. The two semi-circular notches thus formed in the meeting ends of a pair of the grid sections provide a circular opening to receive the shank of one of the screws 3. When the screw is in position the head thereof overhangs and engages the strips of the grid sections to hold the same against longitudinal movement and cooperate with the 30 side walls of the channel shaped seat B to secure the grid sections in position.

Under some conditions it may be desirable to provide the meeting edges of the complementary strips 4 of the grid sections with 40 corresponding slits adapted to receive dowel members 3 to fasten the strips together. If these dowel members are used the two complementary strips 4 of each grid section are fastened together so that the grid section is 45 handled as a unit.

As shown by the drawings, it may also be desirable to provide short slits or notches 8 in the outer edge of one of the complementary strips 4 of each grid section, said short slits 50 being located at the ends of the strip and providing in effect pilot lights for permitting the flame to pass from one grid section to another grid section, so that when a match is applied to the grid at any point in the length thereof, the flame will quickly travel the full length of the grid. The cross bars 2 of the burner mouth have grooves 15 therein which extend under the notches 8 to provide for a feeding of gas thereto.

60 It is essential in a burner grid that the slits have outlets which are either smaller or substantially the same size as the inlets, since with an outlet which is larger than the inlet there is a lateral spreading of the gas as it leaves the grid and this causes "spread-

ing" of the flame. A flaring or lengthening of the grid slits at the upper ends thereof would be objectionable for this reason, and for the best results it is desirable that the slits in the grid should have a substantially 70 uniform cross section from the bottom to the top of the grid. Any lengthening of the slits at the top of the grid, as shown by Patent No. 1,540,678 which was granted on June 2, 1925 to B. A. Baxter, is undesirable 75 and results in objectionable features which it is one of the objects of this invention to avoid.

The grid sections have a substantial thickness which is preferably at least four times the width of the burner slits. This causes the mixture of gas and air to contact with the walls of the burner slits for a slight period of time before it passes through the grid into the combustion zone. This air and gas mixture as it rises through the manifold is cool and it has a cooling effect on the metal of the grid as it passes through the same, and it will be obvious that this cooling effect could not be obtained to any appreciable extent with a thin grid, since the period of contact between the mixture and metal would then be so small as to have no appreciable cooling effect. The formation of the grid sections from metal bars of substantial size not only produces a strong and durable grid but also provides a grid which comprises a sufficient amount of metal to act in an effective manner to conduct the heat of the flame to the side walls of the 100 manifold. Overheating of the grid is thus prevented and back-firing rendered impossible.

In manufacturing these grid sections the burner slits are cut in the metal, preferably by means of a saw, and it will be obvious that if each burner section was an integral bar it would be extremely difficult to saw the slits therein and have the ends of the slits parallel to the edges of the bar so that the slits would have a uniform cross section from the top of the bar to the bottom thereof. In order to meet this difficulty and permit the slits to be formed by the simple and inexpensive expedient of sawing the same, each grid section is formed of complementary strips. It will be obvious that the slits 5 can be easily and quickly formed in the edges of the strips 4 by means of a saw. The method of making the grid sections accordingly comprises the steps of sawing the slits in the edges of the complementary strips and subsequently assembling the strips in an edge to edge relation, preferably with the sawed slits in registry so that the slits of the two complementary strips cooperate to form elongated burner slits which are uniform in cross section from the top of the grid section to the bottom thereof. By means of this process the grid sections can 110 115 120 125 130

be quickly manufactured in large quantities at small cost, and at the same time a grid is provided which will direct the flame straight and with great buoyancy into the 5 radiant, and the flame is prevented from direct contact with the metal of the grid so that there can be no overheating thereof.

Referring to the burner, the Bunsen tube E is shown as having the end thereof flared 10 at 9 to provide an air inlet, the portion of the tube adjacent the flared end being contracted in the usual manner. The gas delivery nozzle is not shown but enters the flared end of the Bunsen tube in the usual 15 way. As the jet of gas passes through the Bunsen tube air is drawn in through the flared end 9 in the usual manner, and the length of the Bunsen tube is sufficient to insure a steady intake of the required quantity 20 of air. It will be understood that with a long tube there is small possibility that the jet of gas will pass down one side of the tube 25 and enter the mixing chamber and manifold without drawing in a supply of air in the required manner to cause perfect combustion.

The mixing chamber D is integral with the rear end of the Bunsen tube E and is returned with respect thereto. The air and gas 30 follow a curved end wall as they enter the mixing chamber and are given a whirling motion which tends to produce a thorough mixture of the air and gas. The end of the mixing chamber D communicates through 35 an opening in the top thereof with the lower end of the manifold A. A partition 10 extends transversely across the outlet opening of the mixing chamber. The upper strata of the whirling mixture of air and gas in 40 the mixing chamber is deflected upwardly by engagement with the partition 10 on one side thereof, while the lower strata of the air and gas passes under the partition and is deflected upwardly on the opposite side 45 thereof by the end walls of the mixing chamber.

The contracted lower end of the manifold is detachably connected by the coupling C to the mixing chamber, being held in position thereon by suitable fastening members such as the screws 11. The mixture of air and gas passes upwardly into the lower end of the manifold in two substantially equal streams on opposite sides of the partition 10. 50 As the air and gas mixture rises in the manifold it is spread out and caused to enter the narrow flared chamber in the upper end thereof. In order to prevent more of the air and gas from rising at the middle of the manifold than at the ends thereof, the side walls 1 of the manifold are provided with corresponding inwardly projecting ribs 12. These ribs are disposed parallel to the top 55 of the burner and, as shown quite clearly by Figure 8, are wider at the middle por-

tion thereof than at the ends. This provides a smaller space for the upward passage of the air and gas at the middle of the manifold than at the end portions thereof. The space for the passage of the air and gas between the inner edges of the ribs gradually increases from the middle of the manifold toward the ends thereof. These ribs thus tend to spread the air and gas laterally so that it is fed with substantial uniformity to 70 the middle and end portions of the grid. A flame of substantially uniform intensity is produced at all parts of the grid and all of the radiants are heated uniformly. The construction of the burner is such that a proper amount of air is always taken in by the gas 75 and thoroughly mixed therewith by the whirling movement in the mixing chamber D. Furthermore, the provision of the partition 10 and ribs 12 results in a uniform feeding 80 of the air and gas mixture to the grid at all points in the length thereof.

The upper end of the manifold is formed with the channel shaped seat B which receives the grid sections, said grid sections being secured to the ends of the manifold and cross bars 2 by the screws 3. The construction of the grid sections, as previously described, is such that they can be cheaply manufactured, quickly assembled, readily taken out and cleaned at any time, and permit the gaseous fuel to be burned in a highly efficient manner.

The channel shaped seat B is open ended so that it can be readily cut or formed by simple tools which can pass through the open ends of the seat.

Having thus described my invention what I claim as new and desire to secure by Letters Patent of the United States is,

1. The process of making a burner grid which consists in placing a number of strips or bars together, forming a series of continuous slits in the edges of the bars, and then placing the slotted surfaces of the bars in contact so that registering slits which formed portions of a continuous slit complement to provide a rectangular grid opening.

2. The process of making a burner grid which consists in placing a number of metal bars in contact side by side, simultaneously cutting transversely across the surface of the bars a plurality of closely related, narrow and continuous slits, then separating the bars into pairs and placing the slotted edges of the bars in contact so that each pair of slits which formed a part of an aforesaid continuous slit register to form complementary portions of a narrow elongated grid opening.

3. The process of making a burner grid which consists in placing a plurality of bars in side by side relation and simultaneously cutting laterally into the bars a plurality of continuous parallel and narrow slits of uni-

- form cross section in opposing edges of the bars, and then disposing each of such strips in a channel in the burner body with the upper surface of the strip substantially flush with the top of the channel and in such manner that the slits at one side coact with a wall of the channel to provide pilot burner openings and the slits at the other side provide main burner openings.
10. 4. A burner construction consisting of a grid comprising a pair of complementary bars formed with matching-registrable slits to provide long and deep jets, said pairs being arranged side to side so that the pairs of identical slits register to form complementary portions of a grid opening, and a burner body on top of which the bars are seated with their upper sides substantially flush with the top of said body.
15. 5. A burner grid comprising a pair of complementary strips having corresponding slits cut in free edges thereof and assembled in an edge to edge relation with the slits of the complementary strips in registry with each other, each registering slit of one strip being identical in size and shape with the complementary slit of the other strip.

6. A burner grid comprising a plurality of complementary slits each of which has a plurality of strips sawed in a free edge thereof, pairs of said strips being assembled in an edge to edge relation, and dowel elements fitted in certain of the slits to hold the coacting strips together in a unit.

7. A burner grid comprising a pair of complementary, elongated, rectangular strips which are similar in shape and interchangeable with each other, said strips being adapted to be assembled in an edge to edge relation and having a series of slits cut in the edges thereof, certain of said slits constituting main burner openings and others pilot openings.

8. A burner grid comprising a bar having burner openings therein and provided at an end thereof with notches providing openings for pilot lights.

9. A burner grid comprising a strip having comparatively deep slits in an edge portion thereof forming main burner openings, and also having shallow slits in the opposite edge forming openings for a pilot light.

In testimony whereof I affix my signature.
FRANK V. RISINGER.
